(57) **CLAIM**

The ornamental design for a sleep appliance, as shown and described.

DESCRIPTION

FIG. 1 is a top front perspective view of a sleep appliance.

FIG. 2 is a top view thereof.

FIG. 3 is a bottom view thereof.

FIG. 4 is a front view thereof.

FIG. 5 is a rear view thereof.

FIG. 6 is a left side view thereof; and,

FIG. 7 is a right side view thereof.

The broken lines in the figures are included for the purpose of illustrating portions of the sleep appliance that form no part of the claimed design.
